UNITED STATES PATENT OFFICE.

HARRY A. SILVERMAN, OF NEW YORK, N. Y.

PERFORATING APPARATUS.

1,401,822.

Specification of Letters Patent. Patented Dec. 27, 1921.

Application filed July 10, 1920. Serial No. 395,321.

To all whom it may concern:

Be it known that I, HARRY A. SILVERMAN, a citizen of the United States, residing in the borough of Bronx, city and State of New York, have invented an Improvement in Perforating Apparatus, of which the following is a specification.

This invention relates to a perforating apparatus and more particularly to that type of perforating apparatus usually employed in puncturing paper, cloth or other material in making patterns by passing the instrument over the material and along predetermined lines in which the perforations are made at predetermined intervals by the instrument. In this type of apparatus, as heretofore commonly constructed, it has been usual to employ a perforating wheel having a series of peripheral teeth which are employed to make the perforations, the wheel being operated in various manners in the use of the instrument, and in some instances being heated to burn the perforation in the pattern material. In the use of these instruments, however, due to the revolution of the perforating wheel, as will be understood, the teeth or projections in making the perforations enter the perforations at one angle, assume a position at substantially right angles to the material while passing through the material, and leave the material at the opposite angle, this having the tendency to make a more or less irregular perforation. The object of my present invention is to overcome this difficulty and to provide an apparatus in which the perforating device is caused to reciprocate rapidly in the use of the instrument so as to enter and leave the material rapidly so as to make a series of uniform perforations. In carrying out the invention, I also prefer to provide means for heating the perforating tool in a suitable chamber in which it is removably mounted so that it may be readily exchanged for different sized perforating devices for effecting perforations of different diameters. Furthermore, the reciprocating perforating device is preferably moved by the movement of the apparatus over the material, as will be hereinafter more particularly described.

In the drawing:

Figure 1 is a central vertical section and partial elevation of the perforating apparatus made in accordance with my present invention, and

Fig. 2 is a front elevation of the same.

By reference to the drawings, it will be seen that in carrying out this invention I preferably employ a frame 10 made of any suitable material and so formed as to include 60 spaced sets of bracket arms 11 and 12 respectively and a support arm 13. Extending between and journaled in bearings provided therefor at the ends of the bracket arms 12 there is a shaft 14. On this shaft 14 65 traction wheels 15 are mounted, the hubs 16 of the traction wheels being suitably journaled on the shaft 14. On one of the traction wheels 15 there is a gear 17. This gear 17 meshes with a pinion 18 secured on a shaft 70 19 which is journaled in the frame of the apparatus. Also mounted on the shaft 19 is a gear wheel 20. This gear 20 meshes with a pinion 21 mounted on a shaft 22 which is journaled in suitable bearings provided 75 therefor at the extremities of the bracket arms 11. Also mounted on the shaft 22 is a ratchet wheel 23 having in the periphery thereof a predetermined number of teeth 24. It will be understood, of course, that while I 80 have shown a single set of gear connections for driving the ratchet wheel 23 from the traction wheels 15 that both traction wheels may be made drive wheels and a double set of gears employed if the same is necessary or 85 appears advisable.

Extending from and connected to the ends of the bracket arms 12, there is a bearing 25 and at the extremity of the support arm 13 there is also a bearing 26. Mounted so as to 90 reciprocate in these bearings is a heater element 27. The outer wall 28 of the heater element is adapted to fit and move within the bearing 25 and in predetermined positions is provided with apertures or perforations designated by 29. In the upper portion of the heating element there is a conical wall 30, and extending from this there is a reduced end or tube 31 forming the extremity of the heating element which fits within and is 95 movable in the bearing 26. In the bottom of the heating element there is a plug or closure 32, and at a predetermined distance from the top thereof there is a transverse wall 33. The heater element also includes an 100 inner wall 34 which is preferably concentric with the outer wall 28 and is provided with perforations 35 preferably placed in positions similar to those in which the perforations 29 are placed in the outer wall 28 or 110 otherwise. The transverse wall 33 is also provided with a series of openings or pas-

sages indicated at 36 in order to provide for the escape of unconsumed products of combustion to the annular space between the outer and inner walls. The gas is preferably supplied through the frame and a flexible hose 13' leading from the frame to an inlet connection 27' in the lower end of the outer wall of the heater element, although as will be understood, the gas may be supplied by any suitable means, and may be controlled by a supply valve 10'. The gas, as will be understood, passes through and burns at the apertures in the inner wall with the flames extending inwardly so as to heat the perforating iron, as hereinafter described.

One form of perforating iron which may be employed in this apparatus is indicated at 37. This comprises a bar of any suitable material having a materially reduced end 38 at one extremity to be employed as the perforating portion of the iron. The body of the iron passes through an opening provided therefor in the bottom or plug 32 of the heater element and also at its upper or inner end into an aperture provided therefor in the transverse wall 33 so as to assume a central position in the heater element. The perforating iron is preferably maintained in position in the heater element by a latch bar 39 which, as illustrated, is mounted in bearings provided therefor in the outer and inner walls of the heater element, and at its inner end is adapted to enter a recess or groove provided in the proper position therefor in the perforating iron. The latch bar 39 is preferably maintained in its normal position with its extremity in the recess in the heater element by a spring 42 mounted in the bearing 40 and extending between the latch bar and the plug 43 by which the bearing at its outer end is closed. The spring 42 also surrounds a rod 41 which is secured at one end in the latch bar and passes through the plug so that the plug may be withdrawn from its normal position to release the perforating iron in order that when necessary the irons may be changed without necessitating the cooling of the heater element which in some instances is a material advantage and in all instances a saving of much time.

I also employ a tractor bracket 44 which may be connected to the bearings 25 and 26 or otherwise, and curved or shaped in any desired manner so as to extend immediately below the lower end of the perforating iron, at which point the tractor bracket is provided with an aperture 45 through which the perforating end of the iron extends in use, it being understood that this extremity of the tractor bracket is employed to enable the user of the apparatus to follow a predetermined line marked on the material in perforating the same to form a pattern. The heater element furthermore is normally maintained in a raised position with the con-

ical portion 30 thereof against the lower ends of the bearing 26 by means of a spring 47 which extends between a flange 46 on the reduced extremity of the heater element and the upper end of the bearing 26. It will be understood, however, that while I have herein shown and described an apparatus which is designed to be heated by gas, other and equivalent heating means may be employed without departing from the nature and spirit of my invention.

In the use of the apparatus as hereinbefore described, the traction wheels 15 are moved over the material, after the same is marked with the lines defining the pattern to be made, in such a manner that the lower end of the tractor bracket always covers the line in which the perforations are to be made. The turning of the traction wheels imparts a relatively rapid movement to the ratchet wheel 23, as will be readily understood, and this causes a reciprocation of the heater element by each tooth of the ratchet wheel coming into contact with a projection 33' on the heater element against the action of the spring 47 so that as each tooth of the ratchet comes into contact with the extension 33' on the heater element the heater element is depressed, causing the end of the perforating iron to make a hole in the material on the line defining the pattern and as soon as the tooth is free of the projection the spring 47 returns the heater element to its normal position, this being done, of course, before the next succeeding tooth of the ratchet comes into contact with the projection on the heater element. In this manner, as will be understood, the heater element is rapidly reciprocated and in each movement thereof causes a perforation to be made in the material for forming the pattern. Of course it will be understood that the irons may be exchanged as hereinbefore stated to make perforations of different diameters or of various configurations and that the ratchet wheels 23 may also have various numbers of teeth and be made interchangeable so that for a given speed in the operation of the apparatus the number of reciprocations of the heater element may be varied to determine the space between each perforation in the line forming the pattern.

It will also be understood that instead of employing a pair of traction wheels and mounting the heater element and its perforating iron between the same, I may employ a single traction wheel with the heater element arranged at the side thereof, as well as other obvious forms of the construction without departing from the nature and spirit of the invention.

I claim as my invention:

1. A perforating apparatus comprising a frame, a traction wheel mounted therein, a heater element movably mounted in the

frame, a perforating iron in the heater element, and means actuated from the traction wheel for moving the said heater element and perforating iron in said frame.

5 2. A perforating apparatus comprising a frame, a traction wheel mounted therein, a heater element slidably mounted in the said frame, a perforating iron detachably connected in the said heater element, and 10 means operated from the traction wheel for moving the said heater element and iron in the said frame.

3. A perforating apparatus comprising a frame, a traction wheel mounted therein, 15 a vertically mounted reciprocating heater element in the said frame, a perforating iron detachably connected in the said heater element, means actuated by the said traction wheel for imparting a downward movement 20 to the said heater element and perforating iron, and devices for returning and normally maintaining the said heater element and perforating iron in an initial position.

4. A perforating apparatus comprising a frame, a traction wheel mounted therein, a 25 heater element mounted to reciprocate vertically in the said frame, a perforating iron, means for detachably connecting the perforating iron in position in the heater element, and means for actuating the heater element 30 and perforating iron from the traction wheel.

5. A perforating apparatus comprising a frame, a traction wheel mounted therein, a heater element including an outer wall, an inner wall placed concentrically with the 35 outer wall providing an intermediate chamber, with the said walls having apertures therein for the admission of air and gas to be burned interiorly at the apertures in the inner wall, a perforating iron detachably 40 mounted within the inner wall of the heater element, and means for actuating the said heater element and perforating iron from the said traction wheel.

Signed by me this 8th day of July, 1920. 45
HARRY A. SILVERMAN.
